CLAIM

The ornamental design for a wind resistant lighter sleeve, as shown and described.

DESCRIPTION

FIG. 1 is a perspective view of the bottom, front left side of a wind resistant lighter sleeve showing my new design, the opposite side being a mirror image;

FIG. 2 is a perspective view of the top, rear, left side thereof, the opposite side being a mirror image;

FIG. 3 is a perspective view of the bottom, front thereof;

FIG. 4 is a perspective view of the bottom, rear thereof;

FIG. 5 is a left side view thereof, the opposite side being a mirror image, showing the invention in a state of use as applied to a disposable lighter in an undeployed and ready position; and,

FIG. 6 is a left side view thereof, the opposite side being a mirror image, showing the invention in a state of use as applied to a disposable lighter in a deployed position.

The broken lines in the drawings depict a disposable butane lighter that forms no part of the claimed design.
